CHARLES MICHEL DALY, OF NEW YORK, N. Y.

BOTTLE-CLOSURE.

No. 802,200.

Specification of Letters Patent.

Patented Oct. 17, 1905.

Application filed May 15, 1905. Serial No. 260,516.

To all whom it may concern:

Be it known that I, CHARLES MICHEL DALY, a citizen of the United States, and a resident of the city of New York, borough of Manhattan, in the county and State of New York, have invented a new and Improved Bottle-Closure, of which the following is a full, clear, and exact description.

This invention relates to closures for bottles adapted for preventing the refilling of the bottles after they have been emptied, and thus prevent the reuse of the liquid-holding package after its original contents have been removed therefrom.

The invention consists in the novel construction and combination of parts, as is hereinafter described, and defined in the subjoined claims.

Reference is to be had to the accompanying drawings, forming a part of this specification, in which similar characters of reference indicate corresponding parts in all the figures.

Figure 1 is a side view of the neck of a bottle, the improved closure thereon, and a preferred means for removing a cap-seal from the closure and thus permitting the decanting of the contents of the bottle. Fig. 2 is a longitudinal sectional view of the bottle-neck through its center and of the improved closure device, showing the closure-cap sealed for preventing leakage from the bottle during transportation as an article of merchandise. Fig. 3 is a nearly-similar view, but showing the sealing means removed from the cap of the closure and the bottle tilted for decanting its contents, the course of the escaping liquid being indicated by arrows in said figure. Fig. 4 is a perspective view of the valve-case; and Fig. 5 is a sectional plan view of a cupped flange employed as a detail of the closure, taken substantially on the line 5 5 in Fig. 2.

In the drawings, 6 indicates the neck of a bottle formed with a shoulder *a* at a suitable distance from the rounded pouring-lip *b*, this being a common constructive detail for bottles used in putting up various liquids for sale as original packages.

The improved closure for the bottle-neck is designed to take the place of a cork or other sealing means and comprises the following details: A cylindrical valve-case 7 is employed that fits closely within the neck 6, and at a suitable point above the end that is inserted in the neck a petticoat-flange 8 is secured on the exterior surface of the valve-case.

As is shown clearly in Figs. 2 and 3, the

petticoat-flange 8 is joined by its inner edge *c* upon the side wall of the valve-case and thence curves upward, outward, and then downward, thus providing an annular space 60 *c'* between the valve-case and the annular curvature *c*², that spaces apart the double walls of the petticoat, the outer depending flange 8^a of the latter fitting closely against the exterior surface of the bottle-neck 6 when the 65 concave surface of the curvature *c*² is seated upon the rounded lip *b* of the bottle-neck.

A plurality of perforations *d* are formed in the wall of the valve-case 7 opposite the upwardly and outwardly flaring wall of the 70 petticoat-flange 8, and at a suitable distance above the perforations *d* a transverse imperforate partition-wall *e* is secured. A seat *g* is formed on the inner surface of the valve-case 7 at its lower end, and a spherical ball-valve 9 is neatly fitted into the case 7, said valve being introduced before the partition-wall *e* is secured in place.

It will be noted that sufficient space is afforded between the ball-valve 9 and the wall 80 *e* to permit a free passage of liquid through the openings *d* and into the space *c'* if the ball-valve is permitted to roll into engagement with said partition-wall, as appears in Fig. 3.

A cupped flange 10 is formed or secured upon the valve-case 7 at a point nearly opposite the plane of the transverse partition *e* and thence curves outward and upward, terminating at and near the upper edge in an 90 outwardly and downwardly curved rim *h*.

As shown, a plurality of perforations *i* are formed in the wall of the valve-case 7, and a similar series of perforations *j* is formed in the cupped flange 10 immediately above the 95 partition *e*, but not opposite the perforations *i*. A conical cap-piece 11, preferably formed of sheet metal, is shaped to fit closely upon the outer edge of the cupped flange 10 and seat upon the convex upper surface of the 100 rim *h*.

The length of the coniform cap-piece 11 is so proportioned that it will extend slightly below the bead or shoulder *a* on the bottle-neck when the valve-case 7 is inserted therein 105 until the curved portion *c*² of the petticoat-flange 8 seats upon the pouring-lip *b*, and the cap-piece is mounted upon the cupped flange 10.

It will be seen that when the cap-piece 11 110 is in position on the cupped flange 10 it will incase and have contact with the outer sur-

face of the petticoat-flange, that in turn incases the portion of the bottle-neck 6 above the shoulder *a*. A central perforation is formed in the top wall of the cap-piece 11, 5 through which the upper extremity of the valve-case 7 projects slightly and may be therein secured.

A sealing-disk 12 is mounted upon the upper end of the valve-case 7 and is thereon secured by solder, which does not extend to the edge of the disk, but permits a slight crevice *m* to intervene between the disk and top wall of the cap-piece 11, as is shown in Fig. 2.

It is evident that the several parts of the 15 entire closure device hereinbefore described may be assembled ready for service and be applied upon the neck of a bottle upon which it is adapted to fit properly after the bottle has been filled with the liquid it is to contain.

20 When the cap-piece 11 is forced down over the bottle-neck, the lower edge thereof, which projects slightly below the bead or shoulder *a* on the bottle-neck, is turned inward and below said shoulder by suitable means, which 25 will secure the complete closure upon the neck of the bottle. In an annular crevice that may be formed between the bead or shoulder *a* a suitable cement *a'* may be introduced when the cap-piece is mounted upon the neck of 30 the bottle, and said cement when it hardens will render the joint between the neck 6 and cap-piece 11 liquid-tight, as well as aid in holding the cap-piece from displacement.

The sealing-disk 12, which covers the opening in the top of the valve-case 7, may be removed by means of a furcated lever 13, the application of which is shown in Fig. 1, or by using pliers. Said lever which is preferably employed for the purpose indicated is sharpened on the inner edges of its forked limbs *o o*, that are so spaced apart as to permit the introduction of the limbs endwise into the crevice *m*, and thus break the soldered joint between the disk 12 and the top wall of the 45 cap-piece 11, which will afford a free but tortuous passage for liquid from the neck 6 when it is inclined as represented in Fig. 3.

It will be noted that it will be practically impossible to introduce a wire or other instrument into the valve-case 7 below the ball-valve 9 through the lateral openings in said valve-case and in the cupped flange 10, the 50 relative positions of the perforations *i*', *i*, and *d* being such that a wire or the like would 55 have to have such short bends in it that it could not be passed into the valve-case for holding the valve above the perforations *d*. Furthermore, it will be obvious that the peculiar formation of the petticoat-flange 8, that 60 affords the narrow space *c* for the passage of liquid from the perforations *d*, greatly contributes to the security of the device.

Having thus described my invention, I claim as new and desire to secure by Letters Patent—

1. A closure for bottles comprising a valve-case, a petticoat extended in inverted-U shape around the valve-case, a ball-valve in the case, means for holding the ball-valve from escape at the lower end of the valve-case, said case having perforations therein opposite the adjacent wall of the annular petticoat, a transverse partition in the valve-case above said perforations, other perforations being formed in the casing-wall above said partition, a cupped flange on the valve-case near its upper end and having perforations therein, a cap mounted upon the upper extremity of the valve-case that extends therethrough, said cap being securable on the neck of a bottle wherein the valve-case is placed, and means for temporarily sealing the open upper end of the valve-case.

2. A closure for bottles comprising a cylindrical valve-case, a seat within the case at its lower end, an annular inverted-U-shaped petticoat secured by one depending edge on the valve-case above its lower end, said petticoat incasing the upper end of the bottle-neck that receives the valve-case, said case having perforations therein opposite an annular space 90 between it and an upwardly-trending member of the petticoat, a ball-valve neatly fitting in the valve-case and movable therein above the seat, a transverse imperforate partition in the valve-case a distance above the perforations therein, a cupped flange secured on the valve-case and spaced therefrom, said flange and the valve-case having opposed perforations therein, a cap-piece having coniform shape and a perforate top, said cap-piece 100 fitting over the free edge of the cupped flange and also contacting with the outer depending wall of the petticoat, the lower edge of the cap-piece being bent inward for engagement with a shoulder on the neck of a bottle wherein the valve-case is inserted, and means for temporarily closing the upper end of the valve-case.

3. In a device of the character described, the combination with a tubular valve-case, 110 and a perforate cap-piece securable on a bottle-neck, of a sealing-disk mounted over the open upper end of the valve-case and soldered on the cap-piece but leaving a free edge and also leaving a crevice for engagement of a 115 tool for displacing the sealing-disk.

In testimony whereof I have signed my name to this specification in the presence of two subscribing witnesses.

CHAS. MICHEL DALY.
